DRIVER'S SEAT FOR FARM MACHINERY

Gail Mendell, Lakeview, Oreg.

Application November 9, 1937, Serial No. 173,668

2 Claims. (Cl. 155—50)

The present invention relates to a structurally refined and improved seat of the customary form-fitting type used on present day farming implements and machines, and the purpose of the invention is to so devise and mechanically perfect the seat and its supporting means as to promote comfort to the occupant through the well-chosen adoption and incorporation of suitably sensitive cushioning means.

My principal objective is to provide the trade with an ingenious seat construction which is possessed of such characteristics and needed embodiments to render it more aptly fitted for the purposes intended, whereby to generally improve upon the prior art development utilizing the cushioning idea.

As will be hereinafter discerned, one phase of the distinguishable assemblage has to do with that part of the complete ensemble identified as the stand, this having the usual upstanding flexible characteristics, being constructed at its attaching or anchoring end with adjusting means for proper regulation, and being constructed at its opposite end to coordinate with the self-adapting cushioning means.

Primarily, however, the aforementioned specifically adapted cushioning means is the outstanding improvement, said means being interposed between the adapter end of the stand and the form fitting seat and having embodied therein equalizing and shock absorbing springs coordinated with a retention arrangement which allows for relative movement of the seat in relation to the stand to permit the occupant to adapt himself to varying surface conditions without the fear of accidental displacement.

Other features and advantages will become more readily apparent from the following description and drawings.

In the drawings, wherein like numerals are employed to designate like parts throughout the views:

Figure 1 is a side elevational view of the complete assembly perfected in accordance with the present invention.

Figure 2 is a view partly in section and partly in elevation disclosing the essential selection and adaptation of multiple spring devices.

Figure 3 is a top plan view of the seat accommodation or attaching frame unit.

Figure 4 is a view, on an enlarged scale, showing the auxiliary stabilizing and balancing spring assembly.

In the drawings the relatively stationary frame 55 of the farm machine is indicated by the numeral

4. The stand is distinguished at 5, the seat at 6, and the seat cushioning and adapter means at 7.

The stand comprises the customarily upwardly and rearwardly inclined resilient bar or strap iron.

8. The anchoring or attaching end, designated as

5: the shank, is differentiated by the numeral 9 and this is variable.

As a general proposition it is at an approximate obtuse angle to the body or bar

8 and provided with a plurality of bolt holes to accommodate attaching bolts 10.

A wedge type 10 shim 11 is interposed between the end or shank 9 and the frame 4.

These shims will vary in proportion and there may be more than one if necessary to vary the inclination or tilt of the stand as a unit.

This makes it possible to raise and lower 15 the seat 6 to take care of occupants of different stature.

The laterally directed upper head forming end of the stand 12 is in an approximate horizontal plane and of appropriate proportions to accommodate the adapter means 7 as well as the 20

superposed seat 6. Incidentally, the seat is of customary form fitting style or shape as indicated at

13. Hence, it is of no moment except as used in combination with the cushioning adapter which is interposed between it and the stand.

25

The adapter assembly comprises a top plate including a rectangular frame 14 and a central cross piece 15.

Underneath this is a similarly constructed base or bottom plate 16, the latter part being bolted as at 17 to the stand, or rather

30 the end portion 12 of the stand. It will be noted that this portion 12 is apertured and provided

with a depending collar 18 having a double flared bore 19 to accommodate the depending end of

the guide and regulating pin 20. This part 20 35

has its end flanged and riveted as at 21 to the central under side of the top plate, whereby to

allow it to depend slidably through the plate 16 and the collar 18. The corner portions of the

parts 12, 16 and 14 are provided with enlarged 40

bolt holes to accommodate the assembling bolts

22 of which there are eight. The headed ends engage the top plate while the nut equipped ends

23 extend down through and beyond the apertures in the base or foundation 12. Each bolt 45

is equipped with main and auxiliary coiled springs

24 and 25. The springs 24 surround the bolts between the plates 14 and 16. They are the cushioning springs.

The shorter auxiliary springs surround the bolts between the washers 26 and 50 the superposed foundation head 12. These are weaker springs and are calculated to off-set recoil or rebound and are therefore shock absorbers.

It will be noted that the bolt and plate assembly is such as to allow the seat, which is at 55

tached to the plate 14, to have the necessary side and forward play. It is desired to prevent unusual rear shifting since this would tend to unseat the driver. This shifting is governed by 5 making the bolt holes sufficiently large as shown in the drawings, and utilizing the ever important guide pin 20 and its associated collar or socket 18. The shape of the bore 19 will determine, to a large extent, the shifting of the seat. Added 10 to this, however, is the retentive action of the series or pairs of intersecting coiled springs 27 and 28. These are arranged as brought out to advantage in Figure 4 and located around the perimeter of the complete assembly where they 15 distribute strain and stress and add to the uniform balance of the structure as a whole.

While the preferred embodiment of the invention has been shown and described, it is to be understood that minor changes coming within 20 the field of invention claimed may be resorted to if desired.

I claim:

1. A seat supporting stand comprising a lower member having a large central hole therein and 25 a plurality of holes adjacent its edges, a collar attached to the central portion of the under face of said member and having a bore gradually increasing in diameter from its center to both ends with the upper end of the bore in register 30 with the large central hole in the member, an upper plate, a rod having its upper end connected with the central portion of the plate and said rod passing through the large central hole in the bottom member and through the bore of the 35 collar, said rod being of much smaller diameter than the smallest part of the bore, rods carried by the plate and passing through the holes adjacent the edges of the bottom member, said holes be-

ing of much larger diameter than the diameter of the rods, springs on the rods located between the plate and the bottom member, other springs on the lower ends of the rods having their upper ends engaging the bottom face of the bottom member, means on the lower ends of the rods engaged by the lower ends of said other springs. 5

2. A seat supporting stand comprising a lower member having a large central hole therein and a plurality of holes adjacent its edges, a collar 10 attached to the central portion of the under face of said member and having a bore gradually increasing in diameter from its center to both ends with the upper end of the bore in register with the large central hole in the member, an upper 15 plate, a rod having its upper end connected with the central portion of the plate and said rod passing through the large central hole in the bottom member and through the bore of the collar, said rod being of much smaller diameter than the 20 smallest part of the bore, rods carried by the plate and passing through the holes adjacent the edges of the bottom member, said holes being of such larger diameter than the diameter of the 25 rods, springs on the rods located between the plate and the bottom member, other springs on the lower ends of the rods having their upper ends engaging the bottom face of the bottom member, means on the lower ends of the rods engaged by the lower ends of said other springs, 30 and a pair of intersecting diagonally arranged coiled springs adjacent each side of the stand located between the bottom member and the plate and each spring having one end connected with the plate and its other end with the bottom mem- 35 ber.

GAIL MENDELL.
